PROTECTIVE HOOD

Joseph De Grazia, Washington, D. C.

Application September 20, 1945, Serial No. 617,661

14 Claims. (Cl. 2-205)

(Granted under the act of March 3, 1883, as
amended April 30, 1928; 370 O. G. 757)

1

The invention described herein, if patented, may be manufactured and used by or for the Government for governmental purposes, without the payment to me of any royalty thereon.

This invention relates to a protective hood adapted to fit over a gas mask.

In an area contaminated with a vesicant gas, the body of the soldier is protected, at least temporarily, by his uniform, and his face and respiratory organs are protected by a gas mask. However, the back of the head, including the ears, and the neck are exposed to the vesicant action of the gas which quickly causes him to become a casualty.

It is known to equip gas contamination squads with gas-impervious suits which protect the body from head to foot. Such protective suits are impracticable as standard equipment for soldiers because of their weight and bulk, and because of the discomfort caused by the wearing. Such suits would also be useless in a surprise attack because of the length of time needed for putting them on.

The protection against vesicant gas afforded the soldier by his clothing (for instance, shirt, trousers, gloves, shoes) is greatly increased by impregnating it with gas-impervious material. To do the same with conventional headgear, such as toques, winter caps, etc., will not produce the desired result, as they do not fit over the gas mask and do not provide a gas tight seal at their lower edges.

It is therefore an object of this invention to provide a protective hood that can be worn over a gas mask.

Another object is a hood which is light and adapted to be folded compactly when not in use, so that it may be carried in the gas mask container.

Another object of the invention is a hood for protection against vesicant gases, which can be conveniently tightened around the neck of the wearer so as to provide a gas proof seal.

A further object of the invention is a hood construction permitting its lateral expansion, so that it can be slid over a gas mask.

Other objects of the invention will be readily apparent from the following description and appended drawings.

A hood in accordance with the present invention comprises a conventional front panel with a face opening, a conventional back panel, and novel side panels, which permit the hood to expand to a width sufficient to fit over the head of the wearer while he is using his gas mask. Tight-

ening means, such as a drawstring, reduce the width of the hood around the neck of the wearer, so as to provide a gas proof seal. The front, back and side portions are of sufficient length to extend below the neck of the wearer; when the hood is tightened around the neck of the wearer the lowermost portion of the hood flares out so as to lie substantially flat on the shoulder of the shirt or coat of the wearer. The hood is preferably impregnated with a gas-impervious material.

A preferred embodiment of a protective hood in accordance with my invention is shown in the drawings, wherein

15 Figure 1 is a perspective view of the hood in use in connection with a gas mask;

Figure 2 is a front elevation of a hood in accordance with my invention;

Figure 3 is a side view, and

20 Figure 4 is a rear view corresponding to Figure 2;

Figure 5 is a detailed view in perspective, of a portion of the hood, marked 5-5 in Figure 2, viewed from the inside; and

25 Figure 6 is a lay-out of the fabric parts which are component parts of the hood.

More particularly, parts 11 and 11' are, respectively, a left and right front portion or panel of the hood, 12 and 12' are left and right back portions or panels, 13 and 13' are a pair of lateral wing portions or side panels having arcuate outer edges and facing the front, and 14 and 14' are a corresponding pair of lateral ring portions or side panels facing the rear of the hood. A semi-circular cut-out in part 11 and a corresponding cut-out in part 11' define a face opening 15; the lower edge of the face opening 15 is bordered preferably by an arcuate strip of semi-elastic laterally expandable material 16, which houses two drawstrings 17, 17' for the purpose of adjusting the size of the face opening 15.

The hood is assembled in the following manner: Parts 11 and 11' are joined together in a seam extending downwardly from the crown to the upper edge of the face opening 15, and from the lower edge of the face opening 15 to the lowermost edge of the hood. The inner edge of lateral wing portion 13 is sewn to the outer edge of the front portion 11 from a point 23 situated at the lower edge of the hood upwardly along the entire length of the inner edge of lateral wing portion 13; lateral wing portion 13' is correspondingly sewn to front portion 11' upwardly from point 23' situated opposite point 23 at the lower edge of the hood. Lateral wing portion 14 is

joined along the entire length of its inner edge to the outer edge of back portion 12, the seam extending upwardly from point 23; and lateral wing portion 14' is correspondingly joined to the outer edge of back portion 12' in a seam extending upwardly from point 23'. As appears from the foregoing, parts 11, 12, 13, and 14 meet at the point 23, and parts 11', 12', 13' and 14' meet at point 23'. The lower edges and outer edges of lateral wing portions 13 and 14 are joined in a seam, and lateral wing portions 13' and 14' are joined together by a corresponding seam; and back portions 12, 12' are joined to each other by a rear seam extending from the crown of the hood to the lowermost edge thereof, and are joined to front portions 11 and 11' by seams extending from the crown of the hood to the uppermost points of lateral wing portions 13, 14, and 13', 14'. Preferably, the joined-together lower edges of lateral wing portions 13, 14 are sewn to the lower edge of back portion 12 in a seam extending rearwardly from point 23; and a corresponding seam unites the joined-together lower edges of lateral wing portions 13', 14' to lower edge of back portion 12' rearwardly from point 23'. It is obvious that the sequence of assembling operations may be varied at will, without, however, changing the relative relation of the individual component parts.

The hood, as assembled in accordance with the foregoing instructions, now has two pocket-like expansible lateral extensions. These expansible pockets enable the user to draw the hood over bulky headgear, such as a gas mask. Means for tightening the hood around the neck, after it has been put on, are provided as follows:

An oblong rectangular tunnel piece 18 is joined to lateral wing portion 13 and front portion 11 by two substantially horizontal seams along the upper and lower margin of tunnel piece 18, and a corresponding tunnel piece 18' is joined to wing portion 13' and front portion 11'. A third rectangular tunnel piece 19 is joined to back portions 12, 12', substantially in line with tunnel pieces 18, 18', by two substantially horizontal seams along the upper and lower margins of tunnel piece 19. Drawstring means 20 through tunnel pieces 18, 18', 19 permit the spaced tunnel pieces to be drawn together, which results in a tightening of the neck portion, as is, for instance, illustrated in Figure 4. Drawstring 20 may be semi-circular, with ends fastened at points 21, 21', to the outer edges of lateral wing portions 13, 14 and 13', 14'; or the drawstring may be endless (not shown). 22 represents tightening means for drawstring 20, such as a sliding perforated ball.

The foregoing description of an example of a hood, in accordance with my invention, is not to be taken as a limitation of the scope of my invention to the specific construction shown, but rather as an illustration of a preferred manner by which the objects of my invention may be attained. Modifications thereof within the scope of my invention will readily occur to the expert. I therefore intend to claim my invention broadly, and to be limited only by the appended claims.

I claim:

1. A hood comprising a front portion adapted to extend to the shoulders of the wearer and having a face opening, a back portion adapted to extend to the shoulders of the wearer, said front and back portions being joined together at the crown of the hood, wing portions extending laterally of and joining together said front and back portions intermediate the crown and shoulder portions of

the hood, and releasable means for retaining said wing portions in a folded position about the neck of the wearer.

5 2. A hood comprising a front portion adapted to extend to the shoulders of the wearer and having a face opening, a back portion adapted to extend to the shoulders of the wearer, said front and back portions being joined together at the crown of the hood, wing portions extending laterally of and joining together said front and back portions intermediate the crown and shoulder portions of the hood, and means for releasably retaining said wing portions in a folded position about the neck of the wearer and tightening the hood around the neck of the wearer.

10 3. A hood comprising a front portion adapted to extend to the shoulders of the wearer and having a face opening, a back portion adapted to extend to the shoulders of the wearer, said front and back portions being joined together at the crown of the hood, wing portions extending laterally of and joining together said front and back portions intermediate the crown and shoulder portions of the hood, and drawstring means for 20 releasably retaining said wing portions in a folded position about the neck of the wearer and tightening the hood around the neck of the wearer.

25 4. A hood comprising a front panel having a face opening, a back panel, two pairs of side panels, one pair of said side panels joined at their inner edges to said front panel, the other pair of said side panels joined at their inner edge to said back panel, and the outer edge of each side panel joined to the outer edge of the opposite side panel, and releasable means for retaining said side panels in a folded position about the neck of the wearer.

30 5. A hood adapted to extend below the neck of the wearer, comprising a front panel having a face opening, a back panel, two pairs of side panels, one pair of said side panels being joined at their inner edges to said front panel, the other pair of said side panels joined at their inner edges to said back panel, and the outer edge of each side panel joined to the outer edge of the opposite side panel, and releasable means for retaining said side panels in a folded position about the neck of the wearer and tightening the hood around the neck of the wearer.

35 6. A hood adapted to extend below the neck of the wearer, comprising a front panel having a face opening, a back panel, two pairs of side panels, one pair of said side panels joined at their inner edges to said front panel, the other pair of said side panels joined at their inner edges to said back panel, and the outer edge of each side panel joined to the outer edge of the opposite side panel, and drawstring means for retaining said side panels in a folded position about the neck of the wearer and tightening the hood around the neck of the wearer.

40 7. A hood adapted to extend below the neck of the wearer, said hood comprising a front portion having a face opening, a back portion, wing portions joined to and extending laterally of said front and back portions, drawstring means for releasably retaining said wing portions in a folded position about the neck of the wearer and tightening said hood about the neck of the wearer, and means for housing said drawstring, said last-named means comprising spaced-apart substantially horizontal tunnel pieces.

45 8. A hood adapted to extend below the neck of the wearer, comprising a front panel having a face opening, a back panel, two pairs of side pan-

els, one pair of said side panels joined at their inner edges to said front panel, the other pair of said side panels joined at their inner edges to said back panel, and the outer edge of each side panel joined to the outer edge of the opposite side panel, drawstring means for tightening the hood around the neck of the wearer, and drawstring housing means comprising spaced, substantially horizontal tunnel pieces.

9. A hood according to claim 4, wherein the outer edges of said side panels are arcuate.

10. In a hood according to claim 1, drawstring means for adjusting the size of said face opening, and drawstring housing means joined to said front portion in a position bordering said face opening.

11. In a hood according to claim 1, drawstring means for adjusting the size of said face opening, and an arcuate housing for said drawstring means, said housing being joined to said front portion in a position bordering the lower margin of said face opening.

12. A hood comprising a front panel having a face opening, drawstring means for adjusting the size of said face opening, a back panel, and two pairs of side panels, one pair of said side panels joined at their inner edges to said front panel, the other pair of said side panels joined at their inner edges to said back panel, and the outer edge of each side panel joined to the outer edge of the opposite side panel.

13. A hood comprising a front panel having a face opening, drawstring means for adjusting the size of said face opening, an arcuate housing for said drawstring means bordering the lower margin of said face opening, a back panel and two pairs of side panels, one pair of said side panels joined at their inner edge to said front panel, the other pair of said side panels joined at their inner edge to said back panel, and the outer edge of each side

5
6
panel joined to the outer edge of the opposite side panel.

14. A hood adapted to extend below the neck of the wearer, comprising a front panel having a face opening, drawstring means for adjusting the size of said face opening and an arcuate housing for said drawstring means bordering the lower margin of said face opening, a back panel, two pairs of side panels having outer arcuate edges, one pair of said side panels joined at their inner edges to said front panel, the other pair of said side panels joined at their inner edges to said back panel, and the outer edge of each side panel joined to the outer edge of the opposite side panel, drawstring means for tightening the hood around the neck of the wearer, and means for housing said last-named drawstring means in the neck portion of said hood, said last-named drawstring housing comprising spaced, substantially horizontal tunnel pieces.
